UNITED STATES PATENT OFFICE.

ABNER ERWIN RUSSELL, OF BENTON, MISSISSIPPI.

BALE-TIE.

SPECIFICATION forming part of Letters Patent No. 298,410, dated May 13, 1884.

Application filed March 12, 1884. (No model.)

To all whom it may concern:

Be it known that I, A. E. RUSSELL, a citizen of the United States, residing at Benton, in the county of Yazoo and State of Mississippi, have invented certain new and useful Improvements in Cotton-Tie Buckles; and I do hereby declare the following to be a full, clear, and exact description of the invention, such as will enable others skilled in the art to which it appertains to make and use the same.

The object of this improvement is a cotton-tie buckle that will, in its operation, be substantially slotless, and thus prevent the liability to spring loose when the bale is moved or dropped from elevated places. This result is attained by the mechanism illustrated in the drawings herewith filed as part hereof, in which the same letters of reference denote the same parts in all the views.

20 Figure 1 is an inverted view. Fig. 2 is a top view. Fig. 3 represents the same adjusted for the reception of the tie-band. Fig. 4 is a side view of one of the parts. Fig. 5 is a side view of one of the parts. Fig. 6 is an edge view of the part shown in Fig. 4.

A represents the buckle, which is made of metal of suitable thickness and provided with central recess or slot, a'' , reduced and extended from one side to the outer edge, as shown at a , Figs. 1, 3, 4, and 6.

A' represents a thin metal washer, slotted from outer edge, as shown at a' , Figs. 2, 3, and 5, to circular recess a''' , with which the same is provided, as specially illustrated in Fig. 5.

35 The slot a' , in the washer A' , is to be made

from a point out of line with the center of the piece, in order to prevent it from getting in line with the slot a in the buckle A , except when specially adjusted for the purpose of inserting the tie-band B , as shown in Fig. 3. 40 When the tie-band for the side opposite to that shown in the figure is inserted, the washer A' is adjusted, as shown in Fig. 2. After the tie is made, the bale expands and the tie closes on the washer and renders it immovable, thus 45 making the buckle operate substantially the same as if there was no slot in it. The washer A' should be made slightly larger than the buckle A . The tie-band B is riveted around the buckle, as shown at b , Figs. 1, 2, and 3. 50 As the tie-band cannot be slipped out of the buckle, except it is specially adjusted for the purpose, as shown in Fig. 3, and as this cannot be done when the expansive strain of the bale is acting on the buckle and the washer, 55 the result of the mechanism is complete security.

Having explained the construction and operation of my improvement, what I claim as new, and desire to secure by Letters Patent, 60 is—

The buckle and washer constructed substantially as specified, in combination with the tie-band, for the purpose set forth.

In testimony whereof I affix my signature in 65 presence of two witnesses.

ABNER ERWIN RUSSELL.
